(57) **CLAIM**

The ornamental design for an organizer, as shown and described.

DESCRIPTION

FIG. 1 is a top, rear perspective view of the organizer in a closed position;

FIG. 2 is a left side elevation view of the organizer in a closed position;

FIG. 3 is a right side elevation view of the organizer in a closed position;

FIG. 4 is a bottom plan view of the organizer in a closed position;

FIG. 5 is a rear elevation view of the organizer in a closed position;

FIG. 6 is a top plan view of the organizer in a closed position;

FIG. 7 is a front elevation view of the organizer in a closed position;

FIG. 8 is a perspective view of the interior of the organizer in an open position;

FIG. 9 is an elevational view of the exterior of the organizer in an open position;

FIG. 10 is an elevational view of the interior of the organizer in an open position, and a writing pad appearing in broken lines;

FIG. 11 is a bottom plan view of the organizer in an open position;

FIG. 12 is a top plan view of the organizer in an open position;

FIG. 13 is a left side elevation view of the organizer in an open position;

FIG. 14 is a right side elevation view of the organizer in an open position;

FIG. 15 is a front, top, left exploded view of the interior with the organizer in an open position showing the insert removed;

FIG. 16 is a front, top, perspective view of the organizer in an open position showing the compartment slightly open and a separate pocketed leaf contained within the compartment;

FIG. 17 is a cross-sectional view taken along line 17-17 showing the front of the separate pocketed leaf attached at the bottom of the compartment of the organizer;

FIG. 18 is a rear, top, perspective view of the organizer in an open position showing the compartment slightly open and a separate pocketed leaf contained within the compartment;

FIG. 19 is a cross-sectional view taken along line 19-19 showing the rear of the separate pocketed leaf attached at the bottom of the compartment of the organizer;

FIG. 20 is a front elevational view of the insert for the organizer in an open position;

FIG. 21 is a side view of the insert for the organizer in an open position;

FIG. 22 is a front, side perspective view of the insert for the organizer; and,

FIG. 23 is a rear, side perspective view of the insert for the organizer.

The broken lines showing pages are for the purposes of illustrating environment and form no part of the claimed design. The elements of the claimed design are shown detached for ease and clarity of illustration.
